(57) **ABSTRACT**

A smoke detector system is provided. The smoke detector system includes a smoke detection element. The smoke detector system further includes an internal air quality (IAQ) sensor. The IAQ sensor is disposed and configured to confirm whether an alarm issued by the smoke detection element is real or a false alarm.

**VERIFYING A FALSE ALARM ON A SMOKE
DETECTOR USING AN INTERNAL AIR
QUALITY SENSOR**

**CROSS-REFERENCE TO RELATED
APPLICATIONS**

This application claims the benefit of U.S. Provisional Application No. 63/339,113 filed May 6, 2022, the disclosure of which is incorporated herein by reference in its entirety.

BACKGROUND

The following description relates to false alarm verification and, more specifically, to a system and method of verifying a false alarm on a smoke detector using an internal air quality (IAQ) sensor.

Smoke detection can lead to false alarms for various reasons. These include, but are not limited to, faulty equipment, human error, low batteries or an inconsistent power source, unlocked or loose doors and windows, incorrect installation and/or the presence of pets, rodents or insects.

Currently, a user of a smoke detector has to manually check for smoke/fire presence when a smoke detector generates an alarm to verify that there is not a false alarm in effect. In some cases, however, a user will call the fire department directly without verifying the fire presence or false alarm which will unintentionally waste time and resources of the fire department.

BRIEF DESCRIPTION

According to an aspect of the disclosure, a smoke detector system is provided and includes a smoke detection element and an internal air quality (IAQ) sensor disposed and configured to confirm whether an alarm issued by the smoke detection element is real or a false alarm.

In accordance with additional or alternative embodiments, each of the smoke detection element and the IAQ sensor is a standalone device.

In accordance with additional or alternative embodiments, the IAQ sensor includes one or more of a PM2.5 sensor, a PM10 sensor, a fire detecting odor sensor, and a total volatile organic compounds (TVOC) sensor and further includes a CO/CO₂ gas sensor, a temperature sensor and a humidity sensor.

In accordance with additional or alternative embodiments, the smoke detection element and the IAQ sensor are integrated into a single device.

In accordance with additional or alternative embodiments, the IAQ sensor of the single device includes one or more of a PM2.5 sensor, a PM10 sensor, a fire detecting odor sensor, and a total volatile organic compounds (TVOC) sensor and further includes a CO/CO₂ gas sensor, a temperature sensor and a humidity sensor.

In accordance with additional or alternative embodiments, when the smoke detection element issues the alarm, a ramping up of the IAQ sensor is indicative of the alarm being real and a normal response of the IAQ sensor is indicative of the alarm being a false alarm.

According to an aspect of the disclosure, a smoke detector system is provided and includes a smoke detection element, an internal air quality (IAQ) sensor and a network with which the smoke detection element, the IAQ sensor and at least one other connected device are intercommunicative.

2

The IAQ sensor is disposed and configured to confirm whether an alarm issued by the smoke detection element is real or a false alarm.

In accordance with additional or alternative embodiments, 5 a thermostat is intercommunicative with the smoke detection element, the IAQ sensor and the at least one other connected device.

In accordance with additional or alternative embodiments, 10 the at least one other connected device is a portable computing device of a user.

In accordance with additional or alternative embodiments, 15 the portable computing device is a smartphone.

In accordance with additional or alternative embodiments, 20 each of the smoke detection element and the IAQ sensor is a standalone device.

In accordance with additional or alternative embodiments, 25 the IAQ sensor includes one or more of a PM2.5 sensor, a PM10 sensor, a fire detecting odor sensor, and a total volatile organic compounds (TVOC) sensor and further includes a CO/CO₂ gas, a temperature sensor and a humidity sensor.

In accordance with additional or alternative embodiments, 30 the smoke detection element and the IAQ sensor are integrated into a single device.

In accordance with additional or alternative embodiments, 35 the IAQ sensor of the single device includes one or more of a PM2.5 sensor, a PM10 sensor, a fire detecting odor sensor and a total volatile organic compounds (TVOC) sensor and further includes a CO/CO₂ gas sensor, a temperature sensor and a humidity sensor.

In accordance with additional or alternative embodiments, 40 when the smoke detection element issues the alarm, a ramping up of the IAQ sensor is indicative of the alarm being real and a normal response of the IAQ sensor is indicative of the alarm being a false alarm.

According to an aspect of the disclosure, a method of 45 operating a smoke detector system is provided and includes recognizing that a smoke detection element issues an alarm, determining a state of an internal air quality (IAQ) sensor and judging whether the alarm is real or a false alarm based on a result of the determining.

In accordance with additional or alternative embodiments, 50 each of the smoke detection element and the IAQ sensor is a standalone device and the IAQ sensor includes one or more of a PM2.5 sensor, a PM10 sensor, a fire detecting odor sensor, a total volatile organic compounds (TVOC) sensor and further includes a CO/CO₂ gas sensor, a temperature sensor and a humidity sensor.

In accordance with additional or alternative embodiments, 55 the smoke detection element and the IAQ sensor are integrated into a single device and the IAQ sensor of the single device includes one or more of a PM2.5 sensor, a PM10 sensor, a fire detecting odor sensor, a total volatile organic compounds (TVOC) sensor and further includes a CO/CO₂ gas sensor, a temperature sensor and a humidity sensor.

In accordance with additional or alternative embodiments, 60 the determining of the state of the IAQ sensor includes finding that the IAQ sensor is ramping up and the judging includes judging that the alarm is real based on the IAQ sensor ramping up.

In accordance with additional or alternative embodiments, 65 the determining of the state of the IAQ sensor includes finding that the IAQ sensor is responding normally and the judging includes judging that the alarm is the false alarm based on the IAQ sensor responding normally.

These and other advantages and features will become 70 more apparent from the following description taken in conjunction with the drawings.

BRIEF DESCRIPTION OF THE DRAWINGS

The subject matter, which is regarded as the disclosure, is particularly pointed out and distinctly claimed in the claims at the conclusion of the specification. The foregoing and other features and advantages of the disclosure are apparent from the following detailed description taken in conjunction with the accompanying drawings in which:

FIG. 1 is a schematic diagram of a smoke detector system in accordance with exemplary embodiments;

FIG. 2 is a graphical depiction of an operation of the smoke detector system of FIG. 1 in accordance with exemplary embodiments;

FIG. 3 is a schematic diagram of components of a standalone IAQ sensor of the smoke detector system of FIG. 1 in accordance with exemplary embodiments;

FIG. 4 is a schematic diagram of components of an IAQ sensor of the smoke detector system of FIG. 1 that is integrated with a smoke detection element in accordance with exemplary embodiments; and

FIG. 5 is a flow diagram illustrating a method of operating a smoke detector system in accordance with exemplary embodiments.

DETAILED DESCRIPTION

As will be described below, systems and methods are provided that using an IAQ sensor with reference to time along with a smoke detector to automatically validate the presence of smoke without manual intervention during an alarm to provide additional indications to the user and/or the fire department as to whether the alarm is a false alarm.

With reference to FIGS. 1 and 2, a smoke detector system 101 is provided and includes a smoke detection element 110, an IAQ sensor 120 and a network 130, such as a cloud network, with which the smoke detection element 110, the IAQ sensor 120 and at least one other connected device 140 are intercommunicative with the network 130 and with each other. The smoke detection element 110 can be a smoke detector 111. The smoke detection system 101 can further include a thermostat 150, which is intercommunicative with the network 130 and with the smoke detection element 110, the IAQ sensor 120 and the at least one other connected device 140. The at least one other connected device 140 can be a portable computing device of a user and/or a fire department official, such as a smartphone 141.

The IAQ sensor 120 is disposed and configured to confirm whether an alarm issued by the smoke detection element 110 is real or a false alarm. That is, as shown in FIG. 2, when the smoke detection element 110 issues the alarm, a ramping up of values of the IAQ sensor 120 can be read (i.e., by an application installed on the smartphone 141) as being indicative of the alarm being real whereas a normal response of the IAQ sensor 120 with no apparent ramping up of values can be indicative of the alarm being a false alarm.

With reference to FIG. 3, each of the smoke detection element 110 and the IAQ sensor 120 can be a separate standalone device (i.e., the standalone smoke detection element 301 and the standalone IAQ sensor 302). In these or other cases, the IAQ sensor 120 can include one or more of a PM2.5 sensor, a PM10 sensor, a fire detecting odor sensor and a total volatile organic compounds (TVOC) sensor. The IAQ sensor 120 can also include one or more of a CO/CO₂ gas sensor, a temperature sensor and a humidity sensor.

With reference to FIG. 4, the smoke detection element 110 and the IAQ sensor 120 can be integrated into a single device 401 with a microprocessor, such as a host MCU 402.

In these or other cases, the IAQ sensor 120 can include one or more of a PM2.5 sensor, a PM10 sensor, a fire detecting odor sensor and a TVOC sensor. The IAQ sensor 120 can also include one or more of a CO/CO₂ gas sensor, a temperature sensor and a humidity sensor.

With reference to FIG. 5, a method of operating a smoke detector system is provided and includes recognizing that a smoke detection element as described above issues an alarm (block 501), determining a state of an IAQ sensor as described above (block 502) and judging whether the alarm is real or a false alarm based on a result of the determining (block 503). In accordance with embodiments, the determining of the state of the IAQ sensor of block 502 can include finding that the IAQ sensor is ramping up whereupon the judging of block 503 can include judging that the alarm is real based on the IAQ sensor ramping up. In accordance with alternative embodiments, the determining of the state of the IAQ sensor of block 502 can include finding that the IAQ sensor is responding normally whereupon the judging of block 503 can include judging that the alarm is the false alarm based on the IAQ sensor responding normally.

Technical effects and benefits of the present disclosure are that users and fire departments will be able to make better decisions during an alarm about how to respond to the alarm. This which will save time and resources. The present invention also provides second-level verification on the presence of smoke using IAQ sensors. This can be used for automatic verification of the presence of smoke.

While the disclosure is provided in detail in connection with only a limited number of embodiments, it should be readily understood that the disclosure is not limited to such disclosed embodiments. Rather, the disclosure can be modified to incorporate any number of variations, alterations, substitutions or equivalent arrangements not heretofore described, but which are commensurate with the spirit and scope of the disclosure. Additionally, while various embodiments of the disclosure have been described, it is to be understood that the exemplary embodiment(s) may include only some of the described exemplary aspects. Accordingly, the disclosure is not to be seen as limited by the foregoing description, but is only limited by the scope of the appended claims.

What is claimed is:

1. A smoke detector system, comprising:
a portable computing device having an application stored thereon;
a smoke detection element; and an internal air quality (IAQ) sensor disposed and configured to confirm whether an alarm issued by the smoke detection element is real or a false alarm,
wherein, when the smoke detection element issues the alarm:

a ramping up of values of the IAQ sensor is indicative of the alarm being real and is graphed with a first slope, which is read by the application as being indicative of the alarm being real, and a normal response of the IAQ sensor with no ramping up of values of the IAQ sensor is indicative of the alarm being a false alarm and is graphed with a second slope, which differs from the first slope and which is read by the application as being indicative of the alarm being false.

2. The smoke detector system according to claim 1, wherein each of the smoke detection element and the IAQ sensor is a standalone device.

3. The smoke detector system according to claim 2, wherein the IAQ sensor comprises a PM2.5 sensor, a PM10 sensor, a fire detecting odor sensor, and a total volatile organic compounds (TVOC) sensor and further comprises a CO/CO₂ gas sensor, a temperature sensor and a humidity sensor.

4. The smoke detector system according to claim 1, wherein the smoke detection element and the IAQ sensor are integrated into a single device.

5. The smoke detector system according to claim 4, wherein the IAQ sensor of the single device comprises a PM2.5 sensor, a PM10 sensor, a fire detecting odor sensor, and a total volatile organic compounds (TVOC) sensor and further comprises a CO/CO₂ gas sensor, a temperature sensor and a humidity sensor.

6. A smoke detector system, comprising:

a smoke detection element;
an internal air quality (IAQ) sensor; and
a network with which the smoke detection element, the

IAQ sensor and portable computing device are inter-
communicative,

the IAQ sensor being disposed and configured to confirm
whether an alarm issued by the smoke detection ele-
ment is real or a false alarm,

wherein the application has an application stored thereon
and, when the smoke detection element issues the
alarm:

a ramping up of values of the IAQ sensor is indicative of
the alarm being real and is graphed with a first slope,
which is read by the application as being indicative of
the alarm being real, and

a normal response of the IAQ sensor with no ramping up
of the values of the IAQ sensor is indicative of the
alarm being a false alarm and is graphed with a second
slope, which differs from the first slope and which is
read by the application as being indicative of the alarm
being false.

7. The smoke detector system according to claim 6,
further comprising a thermostat which is intercommunica-
tive with the smoke detection element, the IAQ sensor and
the at least one other connected device.

8. The smoke detector system according to claim 6,
wherein the portable computing device is a smartphone.

9. The smoke detector system according to claim 6,
wherein each of the smoke detection element and the IAQ
sensor is a standalone device.

10. The smoke detector system according to claim 9,
wherein the IAQ sensor comprises a PM2.5 sensor, a PM10
sensor, a fire detecting odor sensor, and a total volatile
organic compounds (TVOC) sensor and further comprises a
CO/CO₂ gas sensor, a temperature sensor and a humidity
sensor.

11. The smoke detector system according to claim 6,
wherein the smoke detection element and the IAQ sensor are
integrated into a single device.

12. The smoke detector system according to claim 11,
wherein the IAQ sensor of the single device comprises of a
PM2.5 sensor, a PM10 sensor, a fire detecting odor sensor,
and a total volatile organic compounds (TVOC) sensor and
further comprises a CO/CO₂ gas sensor, a temperature
sensor and a humidity sensor.

13. A method of operating a smoke detector system, the
method comprising:

storing an application on a portable computing device;
recognizing that a smoke detection element issues an
alarm;

determining a state of an internal air quality (IAQ) sensor;
and

judging whether the alarm is real or a false alarm based on
a result of the determining, wherein:

the determining of the state of the IAQ sensor comprises
finding that the IAQ sensor is ramping up in values that
is graphed with a first slope, which is read by the
application, and the judging comprises judging that the
alarm is real based on the application reading the IAQ
sensor ramping up, and

the determining of the state of the IAQ sensor comprises
finding that the IAQ sensor is responding normally with
no ramping up of the values of the IAQ sensor that is
graphed with a second slope, which differs from the
first slope and which is read by the application, and the
judging comprises judging that the alarm is the false
alarm based on the application reading the IAQ sensor
responding normally.

14. The method according to claim 13, wherein:
each of the smoke detection element and the IAQ sensor
is a standalone device, and

the IAQ sensor comprises of a PM2.5 sensor, a PM10
sensor, a fire detecting odor sensor and a total volatile
organic compounds (TVOC) sensor and further comprises
a CO/CO₂ gas sensor, a temperature sensor and a
humidity sensor.

15. The method according to claim 13, wherein:
the smoke detection element and the IAQ sensor are
integrated into a single device, and

the IAQ sensor of the single device comprises a PM2.5
sensor, a PM10 sensor, a fire detecting odor sensor, and
a total volatile organic compounds (TVOC) sensor and
further comprises a CO/CO₂ gas sensor, a temperature
sensor and a humidity sensor.
